METHOD AND APPARATUS FOR POWER AMPLIFICATION

Application filed June 4, 1927. Serial No. 196,423.

My invention is concerned with a new method of using thermionic currents in power amplification and with novel apparatus adapted for use in practicing the method.

5 When a magnetic field is impressed at right angles to the path of an electron stream, the electrons are deflected in a direction perpendicular both to the direction of the magnet field and to the electric field causing the 10 electron flow, the magnitude and direction of the deflection depending upon the strength and relative direction respectively of the two fields.

My invention comprises a method for 15 utilizing, and apparatus for applying, this phenomenon in power amplification of alternating or otherwise varying currents. I cause the current that is to be amplified to create an electromagnetic field at right angles to 20 the flow of electrons from a heated cathode to a plurality of positively charged anodes. I place a shield or shields between the electrodes in such a way as to intercept a part of the electron flow to the various anodes and 25 preferably in such a way as to insure that each anode receives substantially equal current from the heated cathode when the magnetic field strength is zero. The deflection of the electronic current occurring when the 30 magnetic field is not zero is made to cause a change in the distribution of the electronic current to the various anodes without changing substantially the total current received by all of the anodes. In this manner any 35 changes in the direction of strength of the controlling current, that is in the current which creates the magnetic field and therefore determines its strength and direction, are reflected in changes in the currents in the 40 various anode circuits.

The modern practice as exemplified in the use of the well-known three-electrode vacuum tube varies the strength of the current to the anode in response to changes in an 45 electrostatic field applied to the grid. As outlined above my method comprises the maintenance of a substantially constant current with its distribution varied in response to changes in an electromagnetic field. This 50 radical departure from the modern practice

results in the elimination of some of the inherent disadvantages of the three-electrode tube and also results in certain economies in operation all of which will become apparent from the following description of the apparatus and its operation.

For a better understanding of my invention reference should be had to the accompanying drawings of which Figs. 1a, 1b and 1c illustrate diagrammatically the fundamental principles of my invention. Fig. 2 is a cross-sectional view of the preferred form of a vacuum tube constructed to operate according to my invention, and Fig. 3 illustrates diagrammatically one application 65 of my amplifying device.

In Figs. 1a, 1b and 1c, 1 is a coil adapted to carry alternating current; 2 is a filament heated by a battery 3 to which it is connected by leads 4; 5 and 6 are shields of any suitable material and 7 and 8 are metal plates connected in parallel through equal impedances 9 and 10 respectively to the positive terminal of a battery 11, the negative terminal of which is connected to the battery 3. In each of Figs. 1a, 1b and 1c it is assumed that plates, shields and filament are inclosed within an evacuated chamber. It is immaterial whether or not the coil 1 is within this chamber. If no current is flowing in coil 1 then the distribution of the electrons from the filament to the plates and shields will be as shown by the broken lines 28 in Fig. 1a. There will of course be electrons emitted radially in all directions from the filament but only that part of the stream indicated is material to this description. The plates, being symmetrically located with respect to the shields and filament and being at equal potentials with respect to the filament will each receive equal electronic current. If now a current is sent through the coil 1 in an anti-clockwise direction, a magnetic field at right angles to the paper and with its positive direction upward from the paper will be impressed within the coil. This field will deflect the electronic current to the left so that the plate 8 will receive current over a larger area, and the plate 7 over a smaller area, than when no current is flowing

in the coil 1; the total current to both of the plates being substantially the same in either case. With increasing anti-clockwise current in the coil 1, the current to plate 7 and through impedance 9 decreases and the current to plate 8 and through impedance 10 correspondingly increases. A magnetic field strength sufficient to deflect all of the available electronic current to plate 8 is shown in Fig. 1b; the deflected electron stream being indicated by 29. Fig. 1c illustrates similarly the extreme case when all of the available electronic current is received by plate 7 under a field impressed by current flowing in a clockwise direction in coil 1. With alternating or pulsating current through coil 1 the electronic current will therefore be deflected synchronously with the current in the coil first to one plate and then to the other; the current to plate 7 decreasing while that to plate 8 is increasing and vice versa.

To utilize the general principles illustrated in Figs. 1a, 1b and 1c an arrangement such as shown in Fig. 2 is preferred. An evacuated glass tube or bulb, shown in cross-section at 12 is surrounded by the coil 1. The filament 2, within the tube and along the axis of the coil, is heated by current led to the filament by wires 4 from the battery 3. The lead wires from the battery to the filament would be in practice of course introduced into the tube at one end in the usual manner.

The filament 3 is surrounded by a cylindrical shield 5 within the tube and having a comparatively small diameter. The shield is provided with longitudinal slots 13 of uniform width which, in the embodiment illustrated, are four in number and of approximately equal circumferential width with the section of the shield between the slots. The anodes are formed of separated segments 7 and 8 of a second cylinder coaxial with the shield and of a substantially greater diameter; the number of segments being twice that of the slots 13. The spacing of the segments is such that the arc subtended by any slot 13 or section of the shield 5 subtends approximately one-half of each of two neighboring anodes 7 and 8. The anodes 7 are in electrical contact through wires 14 and the anodes 8 are in electrical contact through wire 15. The anodes 7 and 8 are connected through equal impedances 9 and 10 respectively with the positive terminal of the battery 11 which in turn is connected at its negative terminal with the battery 3. The particular method of supporting the anodes, shield and filament within the tube, or in making the electrical connections is immaterial to my invention and may be done in any well-known manner. The axial length of the anodes and shield are preferably equal to or greater than that of the filament and substantially less than that of the coil 1.

The operation of the apparatus of Fig. 2 is similar in all respects with that already described in connection with Figs. 1a, 1b and 1c; the only difference being that the cylindrical arrangement permits a greater proportion of the electrons given off by the filament to contribute to the total current. The distribution of this electronic current when no current is flowing in the coil 1 is shown by the broken lines 28 radiating from the filament; the curved lines 29 indicating the path of the electrons when deflected entirely to plates 8 by a clockwise current in coil 1 of maximum strength for the design of the particular tube. For simplicity that part of the stream of electrons intercepted by the shield 5 is not illustrated.

In the operation of such a tube as that illustrated in Fig. 2 it is highly desirable that the filament temperature be maintained low enough to insure that the lowest potential applied to the plates will be sufficient to draw to the plates all of the electron current passing through the slots 13. If the filament temperature is thus restricted substantially constant total plate current is obtained and variations in the current in coil 1 are proportionately reflected in variations in the currents through impedances 9 and 10. In practice, the impedances 9 and 10 will form the primary of a transformer, the secondary being so connected that decreasing current in impedance 9 will affect the secondary voltage in the same direction as increasing current in impedance 10.

The use of a lower filament temperature than that usually employed in the three-electrode tubes results in a substantial increase in the life of the tube and in additional economy in the size of the battery 3, that is in the so-called "A" battery necessary to supply the filament current. Due to the fact that a tube operated according to my invention passes a constant plate current, the internal resistance of the tube is constant and the errors due to changing tube resistance usually occurring in the modern tubes are eliminated. Furthermore, the internal capacity effects which now comprise perhaps the most serious drawback of the three electrode tubes are eliminated by a tube such as that in Fig. 2 as in operation the capacity between the two sets of plates and the other elements of the tube will always balance each other due to the fact that the potentials at the two sets of plates rise and fall oppositely. The shields 5 may be grounded or given a slight positive or negative potential as desired and as is found preferable for the particular tube and for the particular use to which the tube is put.

In Fig. 3 I have shown diagrammatically two amplifying stages of a radio circuit employing a tube such as that of Fig. 2. For convenience the tube is shown symbolically

as a circle including two plates 9 and 10, a filament 2 and a coil 1. The shield is not illustrated and the various elements are now shown in their relative positions. The "A" 5 battery, 3, supplies current in parallel to the filaments 2. As in the other figures, the plates 7 and 8 are connected through impedances 9 and 10 respectively to the positive terminal of the "B" battery 11, the negative 10 terminal of which is connected to the positive terminal of the "A" battery. An adjustable resistance 16 in the "A" battery circuit controls the filament temperatures. An antenna 17 or other receiver of electromagnetic 15 waves, is connected through the primary winding of a transformer 18 to a ground 19 as in the usual receiving circuit. The secondary winding of the transformer 18 is connected through a variable condenser 20 and 20 inductance 21 with the terminals of the coil 1 of the first tube. The inductance 21 is shown as a separate element. It may, of course, if desired form part of the coil 1. The impedances 9 and 10 of the plate circuits of the tube form the primary windings 25 of a transformer 22 the secondary windings 23 and 24 of which are connected with the coil 1' of the second tube through the usual capacity and inductance elements; the winding 23 being coupled with the impedance 9 and the winding 24 being coupled with the impedance 10. Similarly the impedances 9' and 10' associated with the plates 7' and 8' of the second tube are coupled with secondary 30 windings 23' and 24' of a transformer 22'. The filament circuit is grounded through a connection 25 with the lower end of the antenna circuit and the secondary circuits of the transformers are likewise grounded 35 through connections 26 leading to the wire 25. In each of the connections 26 is a resistance 27.

In operation of the circuit of Fig. 3 electromagnetic waves received by the antenna 45 17 induce alternating voltage in the secondary winding of the transformer 18, causing alternating current to flow through the coil 1 and resulting in an alternating magnetic field within the first tube. The alternating 50 field causes variations in the currents through impedances 9 and 10 in opposite directions as heretofore explained. The coupling of the transformer 22 is such that currents varying oppositely in coils 9 and 10 induce voltages 55 in coils 23 and 24 in the same direction. The current in coil 1' caused by the voltages induced in the windings 23 and 24 will therefore vary correspondingly with that in coil 1. Since the change of voltage in the output 60 circuit from each tube may be many times greater than that in the input coils, the tubes will act as power amplifiers and the voltage variations in the secondary of the transformer 22' will correspond with the variations in voltage occurring in the second-

ary of transformer 18 due to the reception of electromagnetic waves by the antenna.

I have now described my invention and illustrated the preferred form of apparatus embodying the principle of my new method of using thermionic currents in power amplification. I have also shown one application of such apparatus. My invention is not limited, however, to any particular application nor to the particular design of tube illustrated. I believe I am the first to control the distribution of an electronic current by variations in a magnetic field in amplifying devices and as such am entitled to a broad interpretation of my claims. The term "alternating current" as employed in my claims is intended to include broadly any varying current as distinguished from constant direct current and is not intended to limit my device to the amplification of sinusoidal currents.

I claim:

1. The method of amplifying alternating currents which consists in creating a radial electron flow from a heated cathode to a plurality of anodes equidistant therefrom and positively charged with respect thereto and in controlling the distribution of said flow to the anodes responsive to changes in a magnetic field created by the current to be amplified, while maintaining substantially constant the total electronic current received by all of said anodes.

2. In combination with a vacuum tube having a heated cathode and a plurality of positively charged anodes, a cylindrical coil adapted to carry alternating current and surrounding said cathode and anodes and so located with respect thereto as to impress a magnetic field at right angles to said electron flow, and shields interposed between said cathode and said anodes whereby they are exposed to parts only of the stream of electrons from said cathode.

3. In an alternating current amplifying device, a vacuum tube containing a heated filament for the emission of electrons and a plurality of plates radially disposed with respect to said filament and charged positively with respect thereto to receive the electronic current therefrom, means within said tube for intercepting a part of said electronic current, means for creating an alternating magnetic field at right angles to the electronic current and varying with the current to be amplified.

4. The combination comprising a vacuum tube having a heated cathode for the emission of an electron flow and a plurality of anodes radially disposed with respect to said cathode for the reception of a constant fraction of said electron flow, a source of electrical energy for charging said anodes positively with respect to said cathode, connections between said anodes and said source

each provided with equal impedances, and a cylindrical coil adapted to carry alternating current to be amplified and so located as to impress a magnetic field at right angles to said electron flow.

5. An alternating current amplifying device comprising in combination an evacuated vessel, a filament within said vessel adapted to be heated to emit an electronic current, a cylindrical shield within said vessel and surrounding said filament, said shield being provided with axial slots of equal width, a plurality of separated electrically conducting anodes forming a longitudinally interrupted cylindrical surface about said shield and coaxial therewith, said anodes being of approximately equal area and of twice the number of the slots in said shield, electrical connections between alternate anodes, means external to said vessel and connecting through the walls of said vessel with two electrically separated anodes for charging said anodes positively with respect to said filament, and a cylindrical coil coaxial with said filament adapted to carry the current to be amplified whereby a magnetic field varying with said current may be impressed upon the electronic current to deflect said electronic current and thus to vary the distribution of said electronic current to said anodes responsively with changes in the current to be amplified.

6. Apparatus as in claim 5 wherein equal impedances forming the primary of a transformer coil are provided in the connecting lines between said external means and said electrically separated anodes.

7. Apparatus as in claim 5 wherein the anodes are so located with respect to the shield that radii from the filament to the spaces between neighboring anodes bifurcate both the axial slots of the shield and the sections of the shield between the slots.

In testimony whereof, I have signed my name to this specification.

MILTON E. THOMPSON.
